(57) **CLAIM**

The ornamental design for a dining garment as shown and described.

DESCRIPTION

FIG. 1 illustrates a front view of a dining garment, according to our new design;

FIG. 2 illustrates a front view of the dining garment of FIG. 1 with elements of the dining garment re-positioned relative to the view illustrated in FIG. 1;

FIG. 3 illustrates a view of the dining garment of FIG. 1 when worn by a diner; and,

FIG. 4 illustrates a view of the dining garment of FIG. 1 when worn by the diner with elements of the dining garment re-positioned relative to the view illustrated in FIG. 3.

The person shown in broken lines represents environment of the claim that forms no part of the claimed design.

1 Claim, 4 Drawing Sheets
